UNITED STATES PATENT OFFICE

94,609

DESIGN FOR AN ELECTRODE HOUSING

Leroy F. Hobert, Sandusky, Ohio, assignor to
Rainbow Light, Inc., New York, N. Y., a cor-
poration of New York

Application December 24, 1934, Serial No. 54,592

Term of patent 7 years

To all whom it may concern:

Be it known that I, Leroy F. Hobert, a citizen
of the United States, residing at Sandusky, in
the county of Erie and State of Ohio, have in-
vented a new, original, and ornamental Design
for an Electrode Housing, of which the follow-
ing is a specification, reference being had to the
accompanying drawing, forming part thereof.

Figure 1 is a view in perspective of an electrode
housing embodying my design;

Figure 2 is a view in bottom plan of the housing
as illustrated in Figure 1.

I claim:—

The ornamental design for an electrode hous-
ing, as shown.

LEROY F. HOBERT.
